Attorney.

UNITED STATES PATENT OFFICE

FRANK MARION, OF BARRE, VERMONT, ASSIGNOR OF ONE-HALF TO ELWIN L. SCOTT,
OF BARRE, VERMONT

OIL BURNER

Application filed September 2, 1926. Serial No. 133,261.

This application is a continuation in part of my prior application No. 84,410, filed January 28, 1926.

It is an object of the invention to effect an improvement and simplification in the construction of oil burners adapted to be produced in cast metal particularly, although it may be otherwise embodied, and aims to produce one especially suitable for installation in domestic heating systems, and stoves. It is an important advantage of the invention that it is especially adapted to use with low grade fuels and is constructed and operative in such manner that there is minimum liability of impairment of its function by carbonizing of fuel or failure to operate under extreme fluctuations of the fire as is ordinarily experienced in domestic installations. For this reason, it is especially adapted to use in connection with automatic control by thermostats exposed in apartments required to be maintained at a predetermined temperature. It is a specific aim of the invention to construct a burner of this type in which the main flame may be maintained under widely varied operating conditions, and especially obviating liability of extinguishing the flame when operated at a low capacity and when starting from low fire to high fire, thereby obviating need for auxiliary devices, such as the pilot light or hand controls.

It is a special object to embody a burner which will be a combined retort and open pot vaporizer operating at high efficiency. This is especially desirable on account of the fact that many fuel oils carbonize excessively, and the buyer without being aware of this may secure such an oil and quickly choke a retort burner by accumulation of carbon in the passages.

Additional objects, advantages and features of invention reside in the construction, arrangement and combination of parts involved, as will be readily understood from the following description and accompanying drawings, wherein

Figure 1 is a top view of a preferred form of the burner in oblong form;

Figure 2 is an end elevation of this burner.

Figure 3 is a longitudinal section of the burner,

Figure 4 is a detail of the support therefor.

Figure 5 is a cross section of the burner. 55

There is shown a burner which is oblong in plan, with a substantial excess of length over the width, to produce the effects described in forming the flame in the manner of use described. A centrifugal action of 60 the burner on the flame is obtained with peculiar advantage in the oblong burner, in conjunction with a forced draft and a restricted flame opening through the top of the burner, the effect being to cause the flame 65 to assume an enlarged oblong form (as viewed from above when the burner is set with its bottom horizontally), by a new manner of functioning in contradistinction to the forming of an oblong area of flame merely by 70 allowing its exit from an oblong opening. This burner is especially useful in domestic cooking stoves, and elsewhere where such form of flame is desired. The flame opening in the top of the burner is circular, the diameter being less than the width of the chamber in the burner and the opening is located midway of the length of the burner. It will be noted that the inlet for air is at one end of the oblong burner and to one side, so that 75 the air is caused to initially pass closely around the outer wall of the burner, the point of admission of vaporized fuel or gas to the burner being closely adjacent the point of admission of the air. In the resultant ac-

tion of the burner the gas mixture (air and fuel) after moving longitudinally of the burner is found to project itself outwardly through the flame opening in greater volume and to a greater distance than gas moving 80 transversely of the burner as it passes through the opening—that is to say, the flame is projected to greater distances toward the ends of the burner than toward the sides. 85

In accordance with the disclosure in my prior application, air is supplied to the large tangential neck portions of the burner, which I illustrate so as to move at a high rate of speed into the burner. At full normal operation the speed of the air current through 90

the neck is greater than the rate of propagation of the flame, so that burning of fuel immediately at the inlet does not then occur. However, if the control be such that the burner is operated at a maximum capacity when heat is required, and at other times limited to a pilot flame at the jet opening, it will be seen that the flame may burn at the inlet when the operation is restricted without liability of carbonizing at the inlet, owing to the low heating capacity of the flame.

The body 50 of the burner comprises a single casting formed with vertical sides and open throughout at the top. The cover 51 also in one piece includes a block element 52, adapted to fit down into the inlet passage or neck 41'. This block 52 has a face downwardly inclined from the outer end so that it serves to direct the incoming air downwardly toward the bottom of the burner to some extent, having the effect of preventing air from moving to the upper part of the burner before being mixed with fuel vapor. Also, at the side of the passage 41' just at its entrance to the body of the burner, and next the medial line of the burner, a vertical vane 53 is formed integrally with the wall of the burner, inclining part way across the mouth of the entrance 41' approximately at an angle of 45 degrees but stopping short of the outer side of the inlet, whereby the incoming body of air is deflected toward the extreme outer side of the burner as the air moves inward. A longitudinal oil channel 54 is formed at the entrance side of the burner and at the outer end of this channel, immediately adjacent the inlet passage 41', a slightly raised boss or step 55 is formed integral with the bottom, through which an oil inlet aperture 56 is formed at its rearmost part, so that oil entering through the opening 56 will spread out upon the boss 55, and flow into the channel 54 in a thin film more readily adapted to be readily heated. The channel 54 is of moderate width, the boss 55 extending the full width of the channel. The channel is formed by means of a raised rib 57, spaced from the center of the burner and extending throughout its length from adjacent the base of the vane 53 to the far end of the burner, it being considered important that this rib 57 should be rather thin in its upper part, so that it may be rapidly heated so as to effect quick vaporization of oil coming in contact therewith. A distance from the boss 55 inwardly in the channel 54, a transverse dam 58 is formed, and it should be noted that this is of a height slightly less than that of the boss 55, and the apex of the rib 57 is at a distance above the top of the boss 55, but lower than the bottom of the passage 41'. The bottom of this burner is horizontal exteriorly, and the bottom of the channel 54 is flat. The upper surface of the bottom from the base of the rib 57 opposite

the channel 54 is inclined upwardly toward the distant side of the burner, as at 59, for the double purpose of affording a thickened body of metal which is adapted to accumulate heat, and also to cause the oil body to be quite thin at its edge over the surface 59, facilitating its rapid vaporization after the oil has accumulated sufficiently to overflow the rib 57. A drain outlet 60 is formed in the lower face of the inlet passage 41' in the lower part of which the drain pipe may be fitted in the customary way, the upper part of the opening 60 being extended laterally, if desired, as shown in Figure 10.

In this construction of burner, it is believed it will be understood that the entering air will tend to move oil admitted through the opening 56 rapidly toward the opposite end of the burner, so that it will overflow the rib 57 principally at the inner end in case such overflow occurs while a substantial draft is on. It is to be understood that this type of burner is to be operated with high pressure air supply, in accordance with disclosures in my prior application, or other approved practices for the supply of air under forced draft. Owing to the highly efficient functioning of these devices, the quantity of gases required to be moved is much less for the heating of an ordinary domestic boiler than is ordinarily involved in the use of coal, and therefore, in the installation of my invention it is customary to adjust the damper of the ordinary boiler furnace so that the draft therethrough is much restricted. This has an important effect in conserving heat, enabling the burner to be operated at highest capacity, but when operated at low capacity, prevents an excess of cold air entering the furnace or too free an escape of hot gases. In this respect, there is a great advantage over the use of burners which require the damper to be left open in order that there shall be a minimum obstruction to the full movement of gases through the burner.

When the burner is operated with a very hot fire, vaporization of the fuel will occur rapidly on surfaces closely adjacent the inlet, but as the fire is shut down, the burner becomes less heated, and a point is finally reached at which a considerable surface is needed to vaporize the fuel. This is especially true if it becomes necessary to quickly increase the heating action of the device after it has been run with a low fire for a time. A large quantity of oil is then admitted on surfaces which are incapable of vaporizing it rapidly and it will be seen that for such conditions a maximum surface of fuel is exposed to the heat of the flame directly in my burner, as well as spread over a greatly increased area of hot metal. It should be noted that the provision of the transverse dam 58 produces a well portion, in which oil, after flowing across the top surface of the boss 55 will

be caused to again spread over the face of the dam 58 suitably, and also upon the inner bottom portion of the channel 54. For convenience in installation, the burners are each formed with a cylindrical vertical lug 62 on the bottom at a suitable location, upon which the sleeve of a tripod 63 may be slipped, the tripod being made in any approved construction to support the burner at a desired height.

10 The opening through the top of the cover 51 in its relation to the burner as viewed from above is shown in dot and dash lines in Figure 1 at 64.

I claim:

15 1. An oblong chambered burner body having a top with a restricted flame opening, an air inlet conduit in line with one longitudinal side of the chamber and opening on the end of the chamber, a liquid fuel channel in line with the inlet at said one side, a liquid fuel inlet opening formed in an operative feeding relation to said channel adjacent said inlet opening, an elevated spreading surface around said fuel inlet opening, the bottom of the burner opposite said channel being shaped to form oil spreading means.

20 2. A burner structure shaped to form an oblong chamber having a restricted circular flame opening at the top, an air inlet neck portion at one end in line with one side of the chamber, fuel oil inlet means adjacent the air inlet, an oil channel along the one side in line with the inlet and oil spreading surfaces formed on the burner bottom to receive oil 25 moved beyond the channel by entrant air, and means to deflect entrant air toward the said channel.

30 3. A burner consisting of a chambered structure the chamber of which is substantially elongated, said burner having a single central flame opening from the chamber in the upper part materially smaller than the major dimension of the chamber, said chamber having an air inlet at one end immediately 35 adjacent one side shaped to direct entrant air along that side of the chamber, and means to supply ignitable fuel in the burner chamber, whereby when air enters the air inlet at high speed, it will move principally along one 40 side of the chamber, across the far end, return and pass across the end adjacent the inlet, then move beside and inwardly of the body of air previously admitted, mixing with the gases of the fuel and causing the gases 45 leaving the burner to be projected largely toward the ends of the burner forming a flame oblong in plan when the device is in operation.

In testimony whereof I affix my signature.

60 FRANK MARION.
